UNITED STATES PATENT OFFICE.

WARREN W. DOHERTY, OF NEW YORK, N. Y.

WRENCH.

1,196,215.

Specification of Letters Patent. Patented Aug. 29, 1916.

Application filed June 28, 1915. Serial No. 36,847.

To all whom it may concern:

Be it known that I, WARREN W. DOHERTY, a citizen of the United States, residing at New York city, in the county of New York; 5 State of New York, have invented certain new and useful Improvements in Wrenches; and I do hereby declare the following to be a full, clear, and exact description of the invention, such as will enable others skilled in 10 the art to which it appertains to make and use the same.

This invention relates to improvements in wrenches, and particularly to the type of wrenches known as rigid jaw wrenches.

15 One object of the invention is to provide a rigid jaw wrench which is provided with a plurality of interchangeable jaw members whereby the wrench can be made to fit a large number of different sized nuts or screw 20 caps.

Another object is to provide a novel form of removable jaw member and means for holding the jaw member to the wrench.

Other objects and advantages will be apparent from the following description when taken in connection with the accompanying drawing.

In the drawing: Figure 1 is an elevation of a wrench made in accordance with my 30 invention. Fig. 2 is a vertical section on the line 2—2 of Fig. 1, Fig. 3 is a vertical section on the line 3—3 of Fig. 1, Fig. 4 is a perspective view of one of the arm members removed.

35 Referring particularly to the accompanying drawing, 10 represents the shank of the wrench having the heads 11 and 12 respectively on the opposite ends. Each of these heads has a recess 13 in the outer end, the 40 upper and lower walls of which are formed with longitudinally extending V-shaped grooves 14. Rearwardly of each of the heads is a transverse opening 15 formed through the shank in which is rotatably disposed the knurled head of a screw bolt 17 engaged through a longitudinal passage formed in the head. The outer end of the threaded portion of the bolt is disposed within the inner end of the recess 13.

45 The movable, jaw member, as clearly seen in Fig. 4 comprises a pair of leg portions

18 and a connecting end portion 19, the outer longitudinal faces of the leg portions are formed with longitudinal ribs which are oppositely beveled as at 20 to fit within 55 the V-shaped grooves 14 of the head of the wrench. The space between the leg members is adapted to engage diametrically opposite faces of a nut or a screw cap. The outer face of the connecting member 19 has 60 a threaded socket 21 which receives the outer end of the bolt 17. As will be noted in the drawing, the outer sides 22 of the ribs are parallel with each other, and perpendicular to the faces of the legs whereby there are 65 formed small triangular spaces between said sides and the adjacent portion of the walls of the V-shaped grooves. These small spaces thus hold the portions 22 at the sides of the ribs from obstruction by dents or nicks in 70 the walls of the grooves 14. This will facilitate the ready insertion of the jaw members which are used in connection with the wrench so that by interchangeably securing the jaw members within the head of the 75 wrench differently sized nuts and screw caps can be quickly and easily acted on.

What is claimed is:

A wrench comprising a shank, a head on the end of the shank having an open-ended 80 recess formed therein, said recess including parallel walls having longitudinal V-shaped grooves formed therein, a screw disposed in the inner end of the recess, the shank having a transverse opening adjacent the head, 85 a thumb-piece carried by the screw and disposed in the said opening, and a removable jaw block of substantially U-shape and disposed within the recess, said screw engaging in the inner end of the said jaw member and 90 longitudinal ribs formed on the outer faces of the arms of the U-member, said ribs being substantially V-shaped in cross section and having portions of their side walls arranged in parallel relation. 95

In testimony whereof, I affix my signature, in the presence of two witnesses.

WARREN W. DOHERTY.
